TYPEWRITING MACHINE

Seyed Khalil, New York, N. Y., assignor to Royal
Typewriter Company, Inc., New York, N. Y., a
corporation of New York

Application April 6, 1936, Serial No. 73,023

8 Claims. (Cl. 197—25)

This invention relates to new and useful improvements in typewriting machines generally, although more particularly to type actions therefore.

- 5 Among the several objects of the invention are to provide a type action in which the noise of impact is materially reduced; to provide a type bar which is bodily raised and moved rearwardly to printing position; and to provide a 10 toggle in the action which imparts an accelerated speed travel to the type bar until the toggle becomes locked, and a decelerated speed travel to the type bar after the toggle is broken and immediately prior to printing.
- 15 With these and other objects in view which will more fully appear, the nature of the invention will be more clearly understood by following the description, the appended claims, and the several views illustrated in the accompanying drawing.

20 In the drawing:

Figure 1 is an elevation of a type action constructed in accordance with my invention, the parts being shown in different positions during 25 the operation, and

Figure 2 is a detail elevation showing the type bar, the supporting lever, and the toggle links in different positions during the operation.

In the accompanying drawing, I have shown a 30 vertically shiftable platen 5 and a type action which includes a finger key lever 6, the latter being disposed below and in front of the platen and pivoted intermediate its ends as at 7 to the machine frame.

35 A supporting hook-lever 8 is disposed intermediate the key lever 6 and the platen. This hook-lever includes a forwardly and upwardly extending beak 9 and a rearwardly and upwardly extending shank 10, the latter being pivoted intermediate its ends as at 11 to the machine frame and forming a resultant short lever arm 12.

A 3-armed lever 13 is pivoted as at 14^a to the machine frame, and includes two upwardly extending arms 14, 15 and a forwardly and downwardly extending and relatively short arm 16. The pivot 14^a is located directly above the rear end of the key lever 6, and a link 17 is pivotally connected at its upper end to the downwardly extending arm 16 and at its lower end to the rear 45 end of the key lever 6. A link 18 is pivotally connected to the lever arm 15 and to the short lever arm 12. It will be noted that the pivot 14^a of the lever 13 is below the pivot 11 of the hook-lever, and that the lever arms 14, 15 extend above the pivot 11.

The beak 9 and the arm 14 are connected by a toggle which consists of a relatively short link 19 and a relatively long link 20. These links are pivotally connected as at 21, the forward end of the short link 19 being pivoted as at 22 to the upper end of the beak 9, and the rear end of the long link 20 being pivoted as at 23 to the upper end of the lever arm 14.

A type bar 24 which is normally inclined upwardly and rearwardly, is pivoted intermediate 10 its ends as at 25 to the short link 19, and carries at its upper end a type head 26 having upper and lower type characters 26^a and 26^b. A link 27 which is normally disposed in parallelism with the link 19, is pivoted at one end to the beak 9 15 below the pivot 22 as at 27^a and at its other end as at 28 to the lower end of the type bar 24. Thus, it will be seen that the lower portion of the type bar 24 constitutes a lever arm 24^a, which together with the link 26, forms a toggle 20 connection between the type bar and the supporting hook-lever 8. It will be noted that the distance between the pivots 27^a and 28 of the link 27 is less than the distance between the pivots 22 and 25 of the short toggle link 19. 25

The hook-lever 8 normally rests on a cushion stop 29 which is secured to the machine frame, and a return spring 30 is connected to the forward arm of the key lever 6 and is anchored on a cross rod 31 also mounted on the machine 30 frame.

In operation, upon depression of the key lever 6, the arm of the intermediate lever 13 will be swung to the right as viewed in Figure 1, and the toggle links 19, 20 will swing the supporting 35 lever 8 upwardly until the links 19, 20 are in locked relation, as shown by the dotted lines in Fig. 1. During the movements of these parts, the type bar 24 will be bodily raised and moved rearwardly until said bar is in a substantially horizontal position as shown by the dotted lines in Fig. 1, and the rate of speed travel of the type bar will be accelerated during said movement. The momentum of the type bar attained during said accelerated speed travel thereof, will suffice 40 for the type bar to break the toggle links 19, 20 and move at a decelerated rate of speed from the single line position shown in Fig. 2 to its printing position as shown by full lines in said figure, and thereby insure a quiet impact against the 45 platen. Upon release of the key lever 6 by the operator, the parts will be returned immediately by the spring 30 to their normal rest positions as shown by full lines in Fig. 1.

It is of course to be understood that the details 55

of structure and arrangement of parts may be variously changed and modified without departing from the spirit and scope of my invention.

I claim:

5. 1. In a type action, a normally upwardly extending type bar, a key lever, and connections between the type bar and the key lever for raising and moving the type bar rearwardly into a horizontal printing position, said connections including a supporting lever, an intermediate lever, and a toggle connecting the supporting lever and the intermediate lever and having pivotal connection with the type bar.
10. 2. In a type action, a normally upwardly extending type bar, a key lever, and connections between the type bar and the key lever for raising and moving the type bar rearwardly into a horizontal printing position, said connections including a supporting lever, an intermediate lever, and a toggle connecting the supporting lever and the intermediate lever and having pivotal connection with the type bar, the upward and rearward movement of the supporting lever effecting the locking of the toggle and the momentum of the type bar effecting a breaking of the toggle and a continued movement of the type bar to printing position.
15. 3. In a type action, a normally upwardly extending type bar, a key lever, and connections between the type bar and the key lever for raising and moving the type bar rearwardly into a horizontal printing position, said connections including a supporting lever, an intermediate lever, a toggle connecting the supporting lever and the intermediate lever and having pivotal connection with the type bar, and a link connecting the supporting lever and the type bar, the upward and rearward movement of the supporting lever effecting the locking of the toggle and the momentum of the type bar effecting a breaking of the toggle and a continued upward and rearward movement of the type bar to printing position.
20. 4. In a type action, the combination with a key lever, of a supporting lever, an intermediate lever connected to the key lever, a toggle link connection between the supporting lever and the intermediate lever, and a type-bar having pivotal connections with the toggle and with the supporting lever.
25. 5. In a type action, the combination with a key lever, of a supporting lever, an intermediate lever connected to the key lever, a toggle link connection between the supporting lever and the intermediate lever, a type bar pivoted intermediate its ends to one of the toggle links, and a link connecting the type bar and the supporting lever.
30. 6. In a type action, the combination with a key lever, of a supporting lever fulcrumed to swing

upwardly and rearwardly, a vertical intermediate lever connected to the key lever to swing rearwardly upon depression of said key lever, a toggle link connection between the intermediate lever and the forward end of the supporting lever and adapted to assume a locked position when the key lever reaches the lower end of its depression stroke, and a type bar having pivotal connections with the toggle and with the forward end of the supporting lever.

5. 7. In a type action, a type bar bodily movable upwardly and rearwardly, a key lever, and connections between the type bar and the key lever including a supporting lever, an intermediate lever, a connection between the intermediate lever and the key lever, a toggle connection between the supporting lever and the intermediate lever, said type bar being pivotally supported on the toggle, and a link connecting the type bar and the supporting lever, said connections accelerating the speed travel of the type bar until the toggle is locked and decelerating the speed travel of the type bar after the toggle has been broken by the continued movement of the type bar due to its momentum.

10. 8. A type action for typewriting machines comprising a platen, a key lever disposed below the platen, a hook-shaped supporting lever disposed intermediate the platen and the key lever and including a forwardly and upwardly extending beak and an upwardly and rearwardly extending shank, the shank being fulcrumed intermediate its ends to form a resultant short lever arm, a vertically disposed intermediate lever fulcrumed intermediate its ends between the supporting lever and the key lever, said intermediate lever having two arms at its upper end and a forwardly and downwardly extending arm at its lower end, a link connecting the downwardly extending arm of the intermediate lever and the rear end of the key lever, a link connecting one of the upper arms of the intermediate lever and the short arm of the supporting lever, a toggle connection between the beak of the supporting lever and the other upper arm of the intermediate lever, said toggle comprising pivotally connected short and long links, the short link being pivoted to said beak and the long link being pivoted to said upper arm, an upwardly and rearwardly inclined type bar pivoted intermediate its ends to the short link of the toggle, and a link connecting said beak and the lower end of the type bar, the distance between the pivots of the last mentioned link being less than the distance between the fulcrum pivot of the short toggle link and the pivot between said short link and the type bar.

25. SEYED KHALIL.
